Primary Examiner — Bridget L Eland*Assistant Examiner* — Lauren D McVey(74) *Attorney, Agent, or Firm* — Meyertons, Hood, Kivlin, Kowert & Goetzel, P.C.; Marc R. DeLuca(57) **CLAIM**

The ornamental design for a cutting plotter, as shown and described.

DESCRIPTION

FIG. 1 is a front, top and right side perspective view of a cutting plotter; showing our new design in a closed position; FIG. 2 is a front, top and right side perspective view of the cutting plotter of FIG. 1, shown in an open position in order to show aspects of the design not otherwise apparent; FIG. 3 is a front elevation view of the cutting plotter of FIG. 1;

FIG. 4 is a rear elevational view thereof;

FIG. 5 is a top plan view thereof;

FIG. 6 is a bottom plan view thereof;

FIG. 7 is a right side elevational view thereof; and, FIG. 8 is a left side elevational view thereof.

The broken lines immediately adjacent the shaded areas represent the bounds of the claimed design while all other broken lines are directed to environment and are for illustrative purposes only; the broken lines form no part of the claimed design.
